UNITED STATES PATENT OFFICE.

WILLIAM J. MEIKLEHAM, OF DENVER, COLORADO.

BAKE-FURNACE.

SPECIFICATION forming part of Letters Patent No. 659,175, dated October 2, 1900.

Application filed February 23, 1900. Serial No. 6,304. (No model.)

To all whom it may concern.

Be it known that I, WILLIAM J. MEIKLEHAM, a citizen of the United States of America, residing at Denver, in the county of Arapahoe and State of Colorado, have invented certain new and useful Improvements in Bake-Furnaces; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in bake-furnaces, my object being to provide a construction adapted to increase the durability and efficiency of furnaces of this class; and to these ends the invention consists of 20 the features, arrangements, and combinations hereinafter described and claimed, all of which will be fully understood by reference to the accompanying drawings, in which is illustrated an embodiment thereof.

25 In the drawings, Figure 1 is a vertical longitudinal section taken through the furnace on the line X X, Fig. 3. Fig. 2 is a top or plan view in detail of the oven, which is composed of sheet-iron. Fig. 3 is a cross-section 30 taken on the line W W, Fig. 1. Fig. 4 is a fragmentary section taken on the line Y Y, Fig. 3. Fig. 5 is a section taken on the line Z Z, Fig. 4, viewed in the direction of the arrow.

35 Similar reference characters indicating corresponding parts in the views, let the numeral 5 designate the brick side walls of the structure; 6, the rear wall; 6^a, the front end wall, and 7 the arch-shaped top. The side 40 walls are reinforced by backstays 8, connected by tie-rods 9, which pass through the walls and over the top arch of the furnace. Between the top and bottom of the furnace, above the fire-box, is located an arch 10. 45 From the fire-box 10 two distinct flues 13, separated by a partition 14, lead rearwardly to the rear end wall 6, where they communicate with vertical flues 15, leading upwardly to the top arch 7. The top wall 13^a of each 50 flue 13 merges at its rear extremity into a vertical wall 13^c, located in front of the rear flues 15.

The sheet-iron oven 16 is located in the top of the structure between the top arch 7 above and the middle arch 10 and the flue-walls 13^a 55 below. This oven extends from the end wall 6^a to the flue-wall 13^c in the rear, and it is embraced by the upper part of the side walls 5. The bottom of the oven is centrally supported by the arch 10 in front and by the flue- 60 partition 14 below, which extends from the bottom of the oven to the bottom wall of the furnace. The oven-bottom is further supported by transverse metal bars 17, whose extremities are let into the side walls and the 65 top of the partition 14. The rear extremity of the oven is protected by the vertical wall 13^c. Between the top wall 13^a of each flue 13 and the bottom of the oven there is a closed 70 chamber 4. Above the oven and communicating with the vertical flues 15 at the rear are two flues 18, located between the top arch and the top wall of the oven and separated by an angle-iron partition 19, riveted to the top of the oven and extending forwardly about 75 half the length of the oven, where it forks, as shown at 19^c, the two branches 19^a of the fork continuing diagonally toward the opposite front corners of the oven. These branches terminate before they reach the oven-corners, 80 leaving outlets 18^a from the flues 18 to the central space 20 between the two branches of the partition. The partition 19 and its branches 19^a engage the top arch, whereby the flues 18 are closed, except at their extremities. 85

The heat passes from the fire-box 12 through the flues 13 to the rear end of the furnace, thence upwardly through the flues 15 to the top of the furnace, thence forwardly through the flues 18 above the oven to the space 20 90 above the front part of the oven, and thence out of the furnace through the chimney-flue 21, which is controlled by a damper 22, operated by a rod 23, accessible from the front of the furnace. The top of the oven is supported 95 by bolts 24, passing through the top arch of the furnace-wall. The bottom of the oven is covered with fire-clay tiling, as shown at 25. The arrangement of the hot-air flues leading from the fire-box, as heretofore explained, is 100 such as to concentrate the heat in the space 20 above the oven, whereby the front of the oven is made hottest.

In use the oven is filled with bread, for in-

stance, through the front opening 26, controlled by a hinged door 27. Hence the first bread put in is shoved to the rear extremity of the oven, the last bread put in being in front. As the last bread put in must be the first removed, it is necessary that the front part of the oven should be the hottest in order to obtain the best possible results from a furnace of this character.

10 The object of the double flues 13, 15, and 18 is to properly distribute the heat to both sides of the oven. If a single continuous flue only were employed, one side of the oven would often be made hotter than the other 15 side by reason of the tendency of the heat to accumulate at one side of the oven more than on the other side. This phenomenon is observed by persons accustomed to the use of furnaces of this class and while not always 20 explainable is nevertheless true. By the double-flue system this difficulty is largely overcome, since the heat after leaving the fire-box is compelled to travel on opposite sides of the furnace until the space 20 is reached. The 25 chambers 4 retain the heat and prevent the bottom of the bread from burning in the oven. The fire-box is accessible through an opening 28, controlled by a door 29.

Having thus described my invention, what 30 I claim is—

1. In a bake-furnace, the combination of a fire-box, an oven extending lengthwise of the furnace and having its front portion above the fire-box, a flue passing beneath the oven 35 and upwardly at the rear end of the oven, a chamber above the roof of the oven, with which the upwardly-extending rear flue communicates, dividing the said chamber above the oven into three compartments, namely a 40 flue extending lengthwise of the furnace on each side of the partition, and a central compartment located between the fork-arms of the partition and above the front part of the

oven, said central compartment being connected with the said flues at their forward extremities, and an outlet-flue communicating with the central compartment. 45

2. In a bake-furnace, the combination of a fire-box, an oven extending lengthwise of the furnace and having its front portion above 50 the fire-box, a divided flue passing beneath the oven and upwardly at the rear end of the oven, a chamber above the roof of the oven, a partition dividing said chamber into two side flues communicating respectively with 55 the flues leading from the fire-box, the said partition being forked above the front portion of the oven and inclosing a central space communicating with the forward extremities of the side flues, and an outlet-flue communicating with the said central compartment. 60

3. In a bake-furnace, the combination with the outer walls of the furnace and a fire-box, of a metal oven extending lengthwise of the furnace and having its front portion above 65 the fire-box, a flue passing beneath the oven and upwardly at the rear end of the oven, a chamber above the roof of the oven with which the upwardly-extending rear flue communicates, a forked partition dividing the 70 said chamber above the oven into three compartments, namely the flue extending lengthwise of the furnace on each side of the partition, and a central compartment located 75 between the fork-arms of the partition and above the front part of the oven, the said central compartment communicating with the said flues at their forward extremities, and an outlet-flue communicating with the 80 said central compartment.

In testimony whereof I affix my signature in presence of two witnesses.

WILLIAM J. MEIKLEHAM.
